(57) **CLAIM**

The ornamental design for a pet grooming vacuum kit, as shown and described.

DESCRIPTION

FIG. 1 is a front perspective view of the pet grooming vacuum kit of FIG. 67, showing the first component separately for clarity of illustration;

FIG. 2 is a bottom perspective view thereof;

FIG. 3 is a front view thereof;

FIG. 4 is a rear view thereof;

FIG. 5 is a left side view thereof;

FIG. 6 is a right side view thereof;

FIG. 7 is a top plan view thereof;

FIG. 8 is a bottom plan view thereof;

FIG. 9 is a right perspective view thereof, but shown in a position of use.

FIG. 10 is a left perspective view thereof.

FIG. 11 is a front perspective view of the pet grooming vacuum kit of FIG. 67, showing the second component separately for clarity of illustration;

FIG. 12 is a bottom perspective view thereof;

FIG. 13 is a front view thereof;

FIG. 14 is a rear view thereof;

FIG. 15 is a left side view thereof;

FIG. 16 is a right side view thereof;

FIG. 17 is a top plan view thereof;

FIG. 18 is a bottom plan view thereof.

FIG. 19 is a front perspective view of the pet grooming vacuum kit of FIG. 67, showing the third component separately for clarity of illustration;

FIG. 20 is a bottom perspective view thereof;

FIG. 21 is a front view thereof;

FIG. 22 is a rear view thereof;

FIG. 23 is a left side view thereof;

FIG. 24 is a right side view thereof;

FIG. 25 is a top plan view thereof;

FIG. 26 is a bottom plan view thereof.

FIG. 27 is a front perspective view of the pet grooming vacuum kit of FIG. 67, showing the fourth component separately for clarity of illustration;

FIG. 28 is a bottom perspective view thereof;

FIG. 29 is a front view thereof;

FIG. 30 is a rear view thereof;

FIG. 31 is a left side view thereof;

FIG. 32 is a right side view thereof;

(Continued)

FIG. 33 is a top plan view thereof;
 FIG. 34 is a bottom plan view thereof.
 FIG. 35 is a front perspective view of the pet grooming vacuum kit of FIG. 67, showing the fifth component separately for clarity of illustration;
 FIG. 36 is a bottom perspective view thereof;
 FIG. 37 is a front view thereof;
 FIG. 38 is a rear view thereof;
 FIG. 39 is a left side view thereof;
 FIG. 40 is a right side view thereof;
 FIG. 41 is a top plan view thereof;
 FIG. 42 is a bottom plan view thereof.
 FIG. 43 is a front perspective view of the pet grooming vacuum kit of FIG. 67, showing the sixth component separately for clarity of illustration;
 FIG. 44 is a bottom perspective view thereof;
 FIG. 45 is a front view thereof;
 FIG. 46 is a rear view thereof;
 FIG. 47 is a left side view thereof;
 FIG. 48 is a right side view thereof;
 FIG. 49 is a top plan view thereof;
 FIG. 50 is a bottom plan view thereof.
 FIG. 51 is a front perspective view of the pet grooming vacuum kit of FIG. 67, showing the seventh component separately for clarity of illustration;
 FIG. 52 is a bottom perspective view thereof;
 FIG. 53 is a front view thereof;
 FIG. 54 is a rear view thereof;
 FIG. 55 is a left side view thereof;
 FIG. 56 is a right side view thereof;
 FIG. 57 is a top plan view thereof;
 FIG. 58 is a bottom plan view thereof.
 FIG. 59 is a front perspective view of the pet grooming vacuum kit of FIG. 67, showing the eighth component separately for clarity of illustration;
 FIG. 60 is a bottom perspective view thereof;
 FIG. 61 is a front view thereof;
 FIG. 62 is a rear view thereof;
 FIG. 63 is a left side view thereof;
 FIG. 64 is a right side view thereof;
 FIG. 65 is a top plan view thereof;
 FIG. 66 is a bottom plan view thereof.
 FIG. 67 is a front perspective view of a pet grooming vacuum kit, showing my new design with all components shown in an assembled state for clarity of illustration.
 FIG. 68 is an enlarged detail view of area 68 in FIG. 11;
 FIG. 69 is an enlarged detail view of area 69 in FIG. 12;

FIG. 70 is an enlarged detail view of area 70 in FIG. 27; and, FIG. 71 is an enlarged detail view of area 71 in FIG. 59. The broken lines in the drawings illustrate the portions of the pet grooming vacuum kit, which form no part of the claimed design. The dash-dot-dash broken lines represent the boundaries and indicators of the enlarged views that form no part of the claimed design.
